EYELASH CURLER AND MASCARA APPLIER

Ada Marcellus, New York, N. Y.

Application January 3, 1946, Serial No. 638,797

9 Claims. (Cl. 132—32)

1

This invention relates to new and useful improvements in an eyelash curler and mascara applier.

More particularly the invention proposes a new and improved eyelash curler and mascara applier, which is arranged to conveniently apply mascara, or petroleum jelly or other substances of the eyelashes while curling them. It is proposed to so construct the curler and applier that it may also be used for applying false eyelashes to the ends of the natural eyelashes.

More particularly the invention proposes to characterize the new and improved eyelash curler by the fact that a brush is removably associated with it, and positioned so as to apply mascara, or petroleum jelly, or other substances to the eyelashes while the eyelashes are being curled.

The invention contemplates a simple construction by which the brush may be easily removed and replaced, as desired.

It is also proposed to so construct the curler that a top rest portion may engage against the bone beneath the eyebrows so as to steady the curler while being used.

The invention also proposes an arrangement by which the brush may be adjusted to various positions in relation to the eyelash curler, so as to control the amount of mascara, or jelly, or other substances applied to the lashes.

Still further the invention proposes a new and improved eyelash curler and mascara applier as briefly explained, which is efficient in operation and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an eyelash curler and mascara applier, embodying this invention.

Fig. 2 is a side elevational view of the curler and applier shown in Fig. 1.

Fig. 3 is a fragmentary enlarged vertical sectional view taken on the line 3—3 of Fig. 1.

Fig. 4 is a fragmentary enlarged detailed view of a portion of Fig. 2 looking in the direction of the line 4—4 thereof.

Fig. 5 is a perspective view of the brush, illustrated per se.

Fig. 6 is a fragmentary side elevational view

similar to Fig. 2 but illustrating a modified form of the invention.

Fig. 7 is a fragmentary elevational view looking in the direction of the line 7—7 of Fig. 6.

5 The eyelash curler and mascara applier, in accordance with that form of the invention disclosed in Figs. 1 to 5 inclusive, includes a stationary curved strip 10 adapted to be engaged against one's eyelid at a point above the eyelashes. The strip 10 is associated with and supported by a handle 11. This handle 11 is formed from a length of wire which is bent at the center to form a finger engaging loop portion 12. The top portions of the side arms 14 of the handle 11 are spaced from each other, and are parallel, and are connected with the ends of the stationary curved strip 10.

A moveable curve strip 16 is engageable against the stationary strip 10 in such a manner as to 20 be capable of clamping the eyelashes between them to curl them in the usual way. The moveable curved strip 16 is in the nature of a length of wire which continues into side arms 17 continuing into a bottom connecting section 18. A 25 resilient member 19 such as a rubber tube is mounted upon said moveable curved strip 16 so as to engage against the bottom edge of the stationary curved strip 10 when these strips are forced together. The moveable strip 16 is associated with handle means by which it may be moved. This handle means comprises a handle 22 formed from a length of wire bent at the center so as to form a finger engaging loop 23. The handle 22 has side arm portions which are pivotally connected intermediate of their ends by a 30 pintle 24 with the handle 11. The ends of the side arms of the handle 22 are formed with openings 25 through which said bottom connecting section 18 pivotally passes. Loop-like guide 35 members 27 are soldered, or in any other way connected with the end portions of the curved strip 16, and slidably engage upon the side arms 14 by which the curved strip 16 is guided towards and away from the stationary gear curve strip 10.

A brush 30 is indirectly connected with the moveable curve strip 16 and is provided with bristles 31 which extend along and slightly above said curve strip 16. The brush 30 has a brush back 32 from which bristles 31 project. This brush back 32 is provided with a projection 33 at the back which may be gripped and serves as a handle by which the brush 30 may be easily removed and replaced upon the curler.

55 The brush 30 is indirectly connected with the

strip 16 by fingers 35 soldered on and projecting from the loop-like guide members 27. These fingers 35 are formed from heavy wire. The brush back 32 of the brush 30 is formed with openings 36 into which the fingers 35 engage. The fingers 35 are substantially parallel. The openings 36 are similarly directed. However, the fingers 35 are offset relative to the openings 36 so that it is necessary to very slightly flex the fingers 35 when the brush 30 is mounted thereon. This resiliency is depended upon to releasably hold the brush 30 in position. Furthermore, the fingers 35 are directed upwards. The brush 30 is placed upon the fingers 35 by moving it downwards. Since the curved strip 16 moves upward to engage the bottom of the curve strip 10, the brush 30 will be naturally clamped in position while the eyelash curler is moved to its closed position.

The handle 11 is associated with top rests 33 adopted to engage beneath the eyebrows and against the eyebrow bone. These top rests 33 are in the nature of small angle members, see Fig. 2. They have relatively flat top portions 39 and substantially vertical side portions 40. The vertical side portions 40 are soldered to inturned ends 41 of the side arms 14 of the handle 11.

The operation of the new and improved eyelash curler and mascara applier may be understood from the following:

The brush 30 may be easily removed by gripping it by the handle projection 33 and pulling it upwards so as to disconnect it from the fingers 35. Now the mascara, or other substances, may be applied to the bristles 31. The brush 30 may be replaced on the fingers 35, or the mascara or other substances may be engaged at the bristles 31 while the brush is in position on the fingers 35. Now the eyelash curler may be used in the usual way. The curved strip 10 is placed against the eyelid directly above the eyelashes. The top rests 33 are engaged beneath the eyebrow and rested against the eyebrow bone. Now the handle 22 is pivoted towards the handle 11 so that the curved strip 16 moves upwards and clamps the eyelashes, which project between the strips 10 and 16, against the bottom edge of the strip 10. While the eyelashes are thus being clamped, the bristles 31 brush against the eyelashes, and transfer the mascara to the lashes.

In Figs. 6 and 7 a modified form of the invention has been disclosed which differs from the prior form in several ways. The inturned end portions 41 of the side arms 14 are provided with small rubber tubes 50 which comprises the top rests for engaging beneath the eyebrow so that the eyelash curler may be steadied. A brush 51 is removably mounted upon the fingers 35. Said brush 51 has lugs 52 at its ends. Adjustment screws 53 turnably engaged through the lugs 52 and engage loop-like guide members 54 which are slidably mounted on the side arms 14. These loop-like guide members are connected with the end portions of the curved strip 16 for movably supporting said curved strip 16. The brush 51 has bristles 55 which are directed against a resilient strip 19 which is mounted on the curve strip 16. The brush 51 is provided with a back projection 56.

In other respects this form of the invention is identical to the prior form and like parts may be recognized by the same reference numerals.

The operation of this form of the invention is identical to the prior form, differing merely in the fact that the screws 53 may be turned in one direction, or the other, so as to move the brush

51 towards or away from the resilient strip 19 of the curved strip 16. The fingers 35 flex during this adjustment. Mascara or other substances may be placed on the bristles 55 of the brush 51 for application as previously explained. The brush 51 may be removed by removing the screw 53 and then forcing the brush 51 upwards and off of the fingers 35.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected to said movable curved strip and having its bristles extending along and slightly above said movable curved strip, and means on said handle for guiding said movable strip in its movement.

2. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected with said movable curved strip and having its bristles extending along and slightly above said movable curved strip, and loop-like guide members slidably mounted upon said handle and connected with the ends of said movable curve strip for guiding said curve strip in its movements.

3. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected to said movable curved strip and having its bristles extending along and slightly above said movable curved strip, and means on said handle for guiding said movable strip in its movement, and fingers projecting from said last mentioned means and engaging openings in said brush by which said brush is removably mounted in position.

4. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected to said

movable curved strip and having its bristles extending along and slightly above said movable curved strip, and means on said handle for guiding said movable strip in its movement, and fingers projecting from said last mentioned means and engaging openings in said brush by which said brush is removably mounted in position, said fingers being of wire and having inherent resiliency for resiliently holding said brush in position.

5. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected to said movable curved strip and having its bristles extending along and slightly above said movable curved strip, and means on said handle for guiding said movable strip in its movement, and fingers projecting from said last mentioned means and engaging openings in said brush by which said brush is removably mounted in position, said fingers being of wire and having inherent resiliency for resiliently holding said brush in position, said handle having side arms with inturned top portions, and top rests mounted upon said top portions.

6. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected to said movable curved strip and having its bristles extending along and slightly above said movable curved strip, and means on said handle for guiding said movable strip in its movement, and fingers projecting from said last mentioned means and engaging openings in said brush by which said brush is removably mounted in position, said fingers being of wire and having inherent resiliency for resiliently holding said brush in position, said handle having side arms with inturned top portions, and top rests mounted upon said top portions, said top rests comprising angle members.

7. An eyelash curler and mascara applier, comprising a stationary curved strip for engagement against one's eyelid at a point above the eyelashes, a handle for supporting said strip, a movable curved strip for engagement against said stationary strip for clamping the eyelashes

against said stationary strip, a resilient strip mounted upon one of said strips for engaging the eyelashes, handle means for moving said movable strip, and a brush connected to said movable curved strip and having its bristles extending along and slightly above said movable curved strip, and means on said handle for guiding said movable strip in its movement, and fingers projecting from said last mentioned means and engaging openings in said brush by which said brush is removably mounted in position, said fingers being of wire and having inherent resiliency for resiliently holding said brush in position, said handle having side arms with inturned top portions, and top rests mounted upon said top portions, said top rests comprising rubber tubes.

8. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, a brush connected with said movable curved strip and having its bristles extending along and slightly above said movable curved strip, and means on said handle for guiding said movable strip in its movement.

9. An eyelash curler and mascara applier, comprising a stationary curved strip for engagement against one's eyelid at a point above the eyelashes, a handle for supporting said strip, a movable curved strip for engagement against said stationary strip for clamping the eyelashes against said stationary strip, a resilient strip mounted upon one of said strips for engaging the eyelashes, handle means for moving said movable strip, and a brush connected with said movable curved strip and having its bristles extending along and slightly above said movable curved strip, loop-like guide members slidably mounted on said handle and connected with said movable curved strip for guiding same, and means for varying the distance of said brush to said movable strips and including adjustment screws connected with said brush and with said 50 loop-like guide members.
